UNITED STATES PATENT OFFICE

JOSEPH D. CEADER AND CARL SEVERIN, OF CLEVELAND HEIGHTS, OHIO, ASSIGNEES
TO GENERAL ELECTRIC COMPANY, A CORPORATION OF NEW YORK

INCANDESCENT LAMP AND MOUNTING THEREFOR

Application filed December 28, 1927. Serial No. 243,107.

Our invention relates to multiple filament electric incandescent lamps and more particularly to projection lamps comprising a plurality of filaments. Our invention is particularly applicable to vehicle headlamps and the incandescent electric lamps used in connection therewith which comprise a plurality of filaments which are so mounted that when the lamp is inserted in its socket, the filaments bear a definite relation to the focus of the usual parabolic reflector forming part of the headlamp. The object of our invention is to provide means which will insure that the lamps are inserted with the filaments properly disposed. Further features and advantages of our invention will appear from the description which follows of species thereof and from the accompanying drawing.

In the drawing Fig. 1 is an elevation of one form of multiple filament lamp; Fig. 2 is an elevation at right angles thereto; Fig. 3 is an elevation of another form of lamp; Fig. 4 is a perspective of part of the mount of the lamp shown in Fig. 1; Fig. 5 is a similar view of the mount of the lamp of Fig. 3; Fig. 6 is a partial perspective showing the lamp base and its socket; Fig. 7 is a bottom plan view of the base; Fig. 8 is a partial elevation of the lamp, its socket and the associated reflector; and Fig. 9 is a diagrammatic view showing the electric circuits.

In Figs. 1 to 5 inclusive are shown two forms of multiple filament incandescent lamps each of which comprises three filaments. In the form shown in Figs. 1, 2 and 4, the lamp comprises the usual bulb 10, base 11 and mount 12. The filaments 13 and 14 are of high candle power and are preferably V-shaped and coiled. The axis of the lamp bulb is in the plane of and passes through the vertex of the V-shaped filament 14. The filament 13 is located in a plane substantially parallel to and at one side of that of the filament 14. The filament 15 is a low candle powered filament which gives a parking light as distinguished from the driving lights which are furnished by either of the other filaments. As shown in Fig. 4, there are four leading-in conductors 16, 17, 18 and

19. Conductor 16 is connected through the conductor support 16' to one end of the filament 13, the other end of said filament being connected to the conductor support X which is mechanically and electrically connected to 55 the conductor support 19'. The conductor 17 is connected through conductor support 17' to one end of the filament 14, and the other end of said filament is connected to the conductor support 19'. The conductor 18 is 60 connected through conductor support 18' to one end of the filament 15, the other end of said filament being connected electrically and mechanically to conductor support X. The leading-in conductor 19 is therefore the common return wire and is connected to the shell 65 of the base. The other conductors 16, 17 and 18 are connected to the base contacts 20, 21 and 22 respectively shown in Fig. 7.

In the form shown in Fig. 3, the driving 70 filaments 13 and 14 are shown as located at opposite sides of the axis of the lamp. The minor or parking filament 15 is located at one side of the filament 14. The connections are shown in Fig. 5 and are similar to those 75 shown in Fig. 4.

As shown in Fig. 6, the base of the lamp comprises a shell having the two projecting pins 23 and 24, which are diametrically opposite, and pin 23 is somewhat closer to the 80 outer end of the base than is the pin 24. A socket 25 is provided with slots 26 and 27, the former being adapted to receive the pin 23 and the other, the pin 24. The slot 26 is consequently somewhat longer than the slot 85 27. This arrangement prevents improper insertion of the lamp in the socket. If it were attempted to invert the lamp, the pin 23 would strike the bottom of the slot 27 before the pin 24 would reach the bottom 90 of slot 26 and it would therefore be impossible to turn the lamp to cause the pins to enter the offset portions 26' and 27' and to lock the lamp in its socket.

In Fig. 8 is shown the reflector 28 of the 95 usual parabolic type and having the lamp socket 25 located centrally thereof. The lamp shown in Figs. 1 and 2 is shown mounted in the said socket, and inasmuch as the filament located at the axis is lowermost, 100

this filament is located at the focus of the reflector. The other filament 13 is above the focus. On account of the provision for the arrangement of pins and slots illustrated in Fig. 6, this arrangement may be 5 uniformly secured.

In Fig. 9 the electrical connections are shown diagrammatically. Leading from one terminal of the battery 29 is conductor 30 connected to switch 31 around which are disposed the switch contacts 32, 33, 34, 35 and 36. A conductor 37 extends from contact 32 to one of the high candle power filaments 13 and from thence to ground 38 through the common conductor 19. The conductor 39 extends from contact 33 to the other high candle power filament 14 and back to ground 38 through conductor 19. Conductor 40 extends from contact 34 to the 10 low candle power filament 15 which is connected to ground 38 through common conductor 19. Conductor 41 connects the contact 35 to the conductor 39 and the conductor 42 connects contact 36 to conductor 37. 15 When the switch 31 engages contact 32 the filament 13 is illuminated; when it engages contact 33, as shown, the filament 14 is illuminated; when it engages contact 34, the parking filament 15 is illuminated; and when 20 it is rotated so as to engage the contacts 35 and 36, both the high candle power filaments 13 and 14 are illuminated in parallel.

What we claim as new and desire to secure by Letters Patent of the United States, 25 is:

1. In a projection lamp, the combination of an incandescent lamp having a base and a plurality of filaments, a socket adapted to receive said base, the base of said lamp 30 having pins projecting laterally therefrom from diametrically opposite points in the periphery thereof and disposed at different distances from the outer end of said base and the socket being provided with corresponding longitudinal slots of different lengths to receive said pins.

2. In a projecting lamp, the combination of an incandescent lamp having a base and a plurality of filaments located differently 35 with respect to the axis of said incandescent lamp and a socket therefor, the base of said lamp having pins projecting laterally therefrom from diametrically opposite sides thereof and disposed at different distances 40 from the outer end of said base and the socket being provided with corresponding longitudinal slots of different lengths to receive said pins.

In witness whereof, we have hereunto set 45 our hands this 23rd day of December, 1927.

JOSEPH D. CEADER.
CARL SEVERIN.
